UNITED STATES PATENT OFFICE.

SAMUEL W. RUSHMORE, OF PLAINFIELD, NEW JERSEY.

COOLING SYSTEM.

Application filed August 10, 1926. Serial No. 128,344.

My present invention is related to that set forth in my companion applications, Ser. Nos. 128,343 and 128,345, in that it concerns cooling systems of the type commonly employed on automobiles or the like, but in which the heat transfer is mainly by boiling or superheating water to absorb surplus heat of the engine and condensing the resultant steam to dissipate said heat in the radiator. Preferably, the boiling is brought about as in my prior Patent No. 1,378,724, granted May 17, 1921, by having a force feed, water circulating system of small heat radiating capacity that serially includes the engine jacket, a conduit therefrom discharging into the base of the radiator and a pump drawing water from said base and force feeding it into the jacket, so that the cooling tubes of the large capacity radiating means are in shunt rather than series relation to the direct path of flow from the water jacket outlet to the pump intake. It is also possible to have some or all of the cooling tubes in series with the pump circuit, some or all of the jacket supply being drawn from the upper chamber and the boiling being brought about by merely limiting the amount of the water supply.

As in said companion applications, the upflow of steam into the honeycomb is controlled by having the radiator full of water, so that liquid flow and liquid resistances will dominate the distribution and upflow of the steam into the radiator tubes.

In said application, Ser. No. 128,345, this liquid circulation is mainly thermal, being primarily induced by the down pressure of cold water in some of the tubes forcing up warmer water in other tubes and then accelerated by ballooning effects of steam in the upflow tubes but, in the present case, I more or less modify or control the thermal circulation tendencies by a forced circulation. When the engine starts, there is relatively feeble, small-volume discharge of water, which is preferably short-circuited to the intake of the pump, so that the water in the jacket soon boils. Preferably, the discharge outlet is throttled or constricted so as to establish back pressure in the engine jacket, sometimes as much as three pounds or more, and so that the steam is discharged into the water in the lower chamber at correspondingly high velocity. Preferably, this discharge is through a surround-

ing tube like an injector tube. The steam and hot water discharged through the tube draw in, mix with and propel relatively large volumes of outside water. The discharge of this composite stream, being lengthwise of the lower chamber, forces water with steam forward and upward in tubes that are in front of the injector and draws cool water downward in tubes in the rear thereof.

The mixing in the injector tube causes condensation of substantial amounts of steam, but as the volume increases, more and more uncondensed steam mingles with and is carried by the water in bubbles which partake of the forced circulation of the water, although the bubbles have an upward ballooning tendency of their own, due to the depth pressure.

The mixing and condensing action of the injector tube also decreases and practically prevents noise and water hammer effects in the lower chamber, but may or may not be sufficient to prevent such effects in the upflow tubes.

In certain cases, the circulation is permitted to distribute itself freely through more or less of the cooling passages of the honeycomb, more of them becoming upflow as the volume and velocity of the steam discharge increases, but in other cases the lower chamber may be partitioned in such a way that certain selected tubes will be exposed only to the suction of the discharge, so that said tubes will always be down-flow. In such case, all of the remaining tubes may be free to become all upflow, or part of them may be neutral, or downflow, according to varying conditions of steam evolution and radiator cooling rates.

The above and other features of my invention will be more evident from the following description in connection with the accompanying drawings, in which:

Fig. 1 is a side elevation conventionally indicating my present system as applied to an automobile engine and radiator, the radiator being shown in transverse section on the line 1—1, Fig. 2;

Fig. 2 is a vertical sectional view of the radiator, approximately on the line 2—2, Fig. 1; and

Figs. 3 to 7 are vertical sectional views of radiators, illustrating modifications of my invention.

In Fig. 1, the motor is conventionally indicated as including the usual crank case 1 and cylinder block 2, the upper parts of which are enclosed by water jacket 3. The water cooling system is conventionally indicated as including the radiator 4, located as usual, on the same level with the motor and directly in front of it so that the lower part of the radiator is below the level of the water jacket of the motor. The circulation of the water from the bottom of the radiator is through a pipe 5 to pump 6, the latter being preferably driven from the engine at directly proportional speeds. The pump is indicated as being a gear pump, but this is merely to illustrate that the pump is one adapted to receive boiling water and force it into the water jacket against friction and any back pressure that may be caused by steaming. The pump discharges through a pipe 7 into water jacket 3, whence the path of flow is through riser outlet 8, and downwardly extending return pipe 9. The pipe 7 may contain a check valve 10 to insure against back flow of water or steam such as might otherwise occur under operating conditions when the engine and pump are stopped. The return pipe 9 connects with a pipe 11, passing through the rear wall of the lower chamber of the radiator and discharging horizontally through two oppositely directed nozzles 13, 13^a.

The radiator is indicated as having the usual lower chamber 12 and upper chamber 15, serving as headers for the intermediate core, indicated in this case as comprising a great multiplicity of small tubes, there being in practice many more than indicated in the drawings. The upper chamber is preferably provided with an overflow pipe 17, which preferably extends into the neck 18, which is closed by a filler cap 19. This overflow pipe is preferably freely opened to atmosphere, although it may be supplied with pressure sustaining breather valves as described in various of my prior patents and applications.

These radiators are thin from front to rear, usually 2 1/4 inches to 3 inches, and the core may consist of tubes which may be, say, 1/4 inch to 3/8 inch diameter. The core may be, say, 21 inches by 24 inches, the usual fan, 20, being of somewhat smaller diameter and, being circular, naturally cools the middle tubes much more than the side tubes.

In such a radiator, even with the bottom compartment entirely unpartitioned, the jets 13, 13^a, naturally tend to apply suction on the central tubes and pressure on the side tubes but, the central tubes being the best cooled tubes, it is desirable to use as many of them as possible as upflow tubes. Therefore, I prefer to limit the region of active suction to a few of the central tubes by partitions 21, 21^a, defining a central compartment, 22, in the suction region of the jets

with two end compartments, 23, 23^a in which the pressure from the jets takes effect. The partitions are formed with passages through which the jets discharge and also with drain holes 24, 24^a affording limited communication between the end compartments and the center compartment. The jets 13, 13^a may be, say 1/16 of an inch in diameter so as to give a very small flow section. The result is to impose a substantial pressure of several pounds on the water jacket, thereby raising the water jacket boiling point up to, say, 218° to 225°, and with the further result that when large volumes of steam are evolved, the jets discharge at high velocity. As shown, 80 the discharge is through Venturi tubes 25, 25^a, whereby water in compartment 22 will be driven by injector action into the end compartment 23, 23^a, thus simultaneously applying suction on the central group of tubes 85 26 and pressure on the side groups of tubes 27, 27, thus definitely determining downflow in the former and upflow in the latter, as indicated by the arrows. There will be some difference in the two cases, however, since 90 the suction in the central compartment takes effect uniformly on all the central tubes regardless of its amount, whereas in case of high velocity discharge, the momentum effects of the jet discharge may apply greater 95 pressure to the outermost tubes. The downflow suction being applied on a few tubes permits a maximum number of the tubes to be utilized for steam-carrying upflow.

This injector arrangement of the jets 100 brings the steam into contact with the in-drawn cool water, under conditions favorable for mixing and scattering the steam so that much condensation will occur without producing objectionable noise or water hammer effects in the lower chamber. The surplus steam, as also superheated water evolving steam in finely subdivided bubbles, tends to follow the flow of the water and the distribution of its flow to the bottoms of the 105 tubes is not materially different from that of the water.

It will be evident that initially the discharge will be of small volume and at low velocity, causing but slight circulation in the 110 tubes; but, when the radiator is taxed to its maximum capacity, the steam with more or less entrained water, will flow very nearly to the tops of the upflow tubes before being 115 condensed. Under such conditions, the side tubes operate as upflow condensers for a greater or less portion of their length, while the central tubes connecting the top tank with the central compartment will act merely 120 as water cooling return drains.

Where a balanced circulation is desired, the intake pipe 5 is branched so as to draw water equally from points 28, 28^a in the respective chambers 23, 23^a, preferably from just below the injector discharge.

The modified radiator arrangements shown in Figs. 3 and 4 function in somewhat the same general way as above described in connection with Figs. 1 and 2, so corresponding parts in Figs. 3 and 4 are indicated by the same reference numerals, but with different exponents for the modified forms. In Figs. 3 and 4 the main difference is that instead of two nozzles discharging oppositely at the center, there is only one nozzle, 13^b in Fig. 3 and 13^c in Fig. 4, and this nozzle is located at one end of the lower chamber instead of at the center. In this way, the circulation in the entire radiator is somewhat like that described above for one of the halves of the radiator of Fig. 1. The single nozzle arrangement has the advantage that the passages most definitely determined as downflow are near the side of the radiator where the tubes are usually less effectively cooled, thus leaving the more central tubes which are better cooled by the direct draft of the fan, freer for invasion by upflow circulation, said upflow being much less definitely predetermined and more likely to shift than in Fig. 1. However, the downflow tubes can be more definitely predetermined by using one partition 21^b as in Fig. 3, but this is not necessary and may be omitted as in Fig. 4. As shown, the nozzle discharges through a venturi 25^b, Fig. 3 and 25^c, Fig. 4, but this may be omitted.

The specific arrangement shown in Fig. 4 has practical advantages for changing small radiators such as those on the well known Ford cars, from downflow water cooling, to upflow steam cooling, the nozzle 13^c being in this case rigidly positioned with respect to the venturi 25^c by casting the parts integrally connected through webs 30^c. The venturi itself has an integral support 31^c, which serves to anchor one end of the casting to the bottom of the radiator while the other end is held by the collar 32^c which has the bottom of the radiator clamped between it and the fitting collar of discharge pipe 9^c.

In Fig. 3, the cooling tubes may be the same as in Figs. 1 and 2, in which case the side tubes 26^b will be most exposed to the suction in the rear of the venturi, although there may be a secondary injector effect operating on tubes further forward by reason of the composite discharge from the front end of the venturi.

Fig. 4 differs from Fig. 3 in that there are cross-flow passages *c*, *c*, in the honeycomb whereby there is more opportunity for the forced circulation to short-circuit without going through the upper chamber, during times when there is little or no steam evolution. As the nozzle is preferably small, however, say, $\frac{1}{2}$ inch or less in diameter, the back pressure in the water jacket will be considerable and when the discharge carries considerable steam, it will be throttled and

of relatively high velocity, thereby establishing water circulation in the cooling tubes and as soon as there is enough uncondensed steam so that considerable amounts of it penetrate the upflow tubes, the up-circulation of the water will acquire a velocity that will carry it into the upper chamber with less tendency to short-circuit through the cross-tubes.

While the conditions and operations of the device are thus widely variable with changing conditions of the same device and are further variable with different proportions of parts, back pressures, temperatures, etc., the circulation results from suction and pressure applied in the lower chamber. Primarily, the heavy water in the down-flow tubes applies static pressure in the lower chamber which pushes up the warmer lighter water into and through the upflow tubes and such push will be increased and, in most cases, practically dominated by the jet suction under some of the tubes and jet pressure under others. The water circulation resulting from these causes will be promoted by the steam because the steam bubbles have a balloon tendency of their own which tends to carry the bubbles upward into the tubes at a rapid rate and when the bubbles are once in the tubes, they decrease the hydrostatic load that the pressure from the down tubes and the jet is overbalancing.

While I have illustrated the honeycomb tubes as being all of the same size, it is obvious that variations are possible, particularly that the down-flow tubes may be much fewer in number provided they have the required down-flow capacity. The space thus saved may be devoted to upflow tubes. Also the entire core may be upflow, the down-flow being through one or more large tubes, outside the radiator.

Even standard equipment radiators of the automobile type vary so widely in construction and proportion and, when operated by my system, the water-carrying steam and steam-carrying water are so widely variable, that detailed consideration of the functioning under any one condition is likely to be misleading, but for general application of my invention, it may be well to note the following difficulties that I have discovered and solved:

For instance, the tubes are characteristically long and thin. A straight cylindrical tube, say, 20 inches high by one-quarter inch diameter will have a flow section of only about one-twentieth of a square inch, so that its total cubic content is about 1 cubic inch. Consequently, if as much as one-quarter of a cubic inch of steam is given opportunity to enter the tube as a single body, without being subdivided into further bubbles by surface tension plus depth pressure, it will fill about 5 inches of the tube; one-half cubic

inch will fill 10 inches of the tube, etc. In the tube, such body or bubble of steam, whatever its length, will be squeezed between the above described dominant pressure from below and the opposing static pressure of the water above, so that primarily it will tend to assume the form of a cylindrical piston with its cylindrical surfaces yieldingly pressed toward the cold walls of the tube. The details of what will happen thereafter either to the condensate or to the bubble as it rises in the tube, need not be followed further than to explain that in its final stage of cooling and condensing, the body of steam collapses and the water rushes into the vacuum at high velocity, being impelled by both atmospheric and depth pressures. The resulting uncushioned head-on collision in the tube between columns of incompressible water, produces a violent shock or water hammer effect which the thin radiator walls effectively apply to the air as cracking and banging noises. This is also accompanied by violent surgings of the water in the upper chamber resulting in excessive losses through the overflow pipe.

Under certain conditions the above operations occur, in repeating cycles, the inflow of steam being by high velocity up-rush intermittently cut off by up-rush of water, and the resulting noises and surging are of practically and commercially prohibitive violence.

In the present case, it will be found that the mixing, condensing and subdividing of the steam in the injector whereby noise is prevented in the lower chamber, will greatly decrease the violence of the above described effects of steam that enters the tubes. The smaller bubbles are less piston like and the surrounding condensate affords them better protection from the walls of the cooling tubes. Furthermore, if the bubbles are small enough, the noise of their collapse will be unnoticeable and a large number of them occurring continuously in the same tube, there will be little or no surging.

However, if the injector action is effective for forcing the desired circulation of water in the tubes and preventing an objectionable amount of noise in the lower chamber, proper distribution and practically noiseless condensation in the tubes may be ensured by suitable flow resistances.

Flow resistances suitable for my present system of water circulation are shown in my companion application Ser. No. 128,343, filed August 10, 1926, wherein the tubes have flow-baffling devices of such a character that they afford small opposition to normal, relatively low speed circulation, but afford practically prohibitive resistance as against high speed flow of water such as can produce objectionable noise effects in the tubes when considerable bodies of steam collapse there-

in. Such flow-baffling devices have also an important function in decreasing the flow section and thereby promoting cut-off and bubble effects reducing sizes of the collapsible bubbles, limiting exposure of the bubble to cooling tube surface, etc., so that the action of the high velocity jet discharge need only be effective enough to keep up active circulation and prevent objectionable noise in the lower chamber. 75

Similar flow resistance effects are obtainable without special forms of flow resistance devices, by employing a honeycomb of the so-called cellular type, wherein the passages have zigzag, or octagonal, or rectangular arrangement, so that high velocity flow therein is baffled by abrupt turns at short intervals. 80

Such a cellular honeycomb is schematically indicated in Fig. 5, wherein parts corresponding to similar parts in the other figures, are indicated by the same numerals but with a different exponent. In Fig. 5 the core or honeycomb consists of tubes 26^a, 27^a, in flattened or "ribbon" form, the width of each tube representing the entire thickness of the honeycomb which may be, say, 2 inches to 3 inches, so that it is possible to flex them to the rectangular arrangement shown. 95

In actual practice, each upflow passage has 80 to 100 or more of these right angle deflections and they are only a quarter of an inch or so apart. Consequently, while offering hardly more than simple friction resistance to ordinary slow flow of water, high velocity flow of considerable columns of water such as will produce noise and water hammer effects is prevented by the right angle impacts every quarter inch of the way, each impact causing obstructing turbulence and whirls in the water. Consequently, the water hammer tendency, in so far as it has any effect, is more likely to cause further mixing and subdividing of the steam bubbles than to produce objectionable noise in the tubes or surging in the upper chamber. This is notwithstanding but rather because of the fact that such ribbon tubes may have thin passages, only $\frac{3}{16}$ to $\frac{1}{4}$ inch thick, in which a bubble of any size may contact with both walls. 100

Fig. 7 is merely to illustrate that the pump may draw part or all of the jacket supply through an intake 27^x in the upper chamber, preferably adjacent the upper end of the side upflow tubes that are in best position to have their circulation forced by the momentum of the stream discharged from the injector. Otherwise the construction is the same as in Fig. 5. 115

As to all forms of my invention, it will be understood that if the cooling capacity be exceeded, as may be the case when a fan belt breaks, the system will continue operative. 120

with more or less loss of steam and water until the water is substantially exhausted, the final stages of the operation being in accordance with the method specifically described in my said Patent No. 1,378,724.

I claim:—

1. An internal combustion engine having a water and steam cooling circuit of inadequate radiating capacity, serially including a force feed pump supplying water to the jacket of the engine, an outlet discharging hot water and steam from the jacket into the lower chamber of an air cooled radiator of the upright type having a multiplicity of small diameter cooling passages of great radiating capacity connecting a lower chamber of small radiating capacity with an upper chamber which has a high level overflow outlet, and in combination with said parts, means for maintaining a circulating body of water submerging and upflowing through some of said cooling passages and downward through others, said means including a discharge means arranged to discharge warm water and then hot water and the steam from the engine lengthwise along a region of said body of water that is below and in proximity to the lower ends of most of said passages and to draw water from a region below other passages.
2. An internal combustion engine having a water and steam cooling circuit of inadequate radiating capacity, serially including a force feed pump supplying water to the jacket of the engine, an outlet discharging hot water and steam from the jacket into the lower chamber of an air cooled radiator of the upright type having a multiplicity of small diameter cooling passages of great radiating capacity connecting a lower chamber of small radiating capacity with an upper chamber which has a high level overflow outlet, and in combination with said parts, means for maintaining a circulating body of water submerging and upflowing through some of said cooling passages and downward through others, said means including an injector discharge device in the lower chamber arranged to discharge hot fluid from the engine lengthwise along a region of said body of water that is below and in proximity to the lower ends of a large number of said cooling passages, the suction intake of said injector being in proximity to the lower ends of relatively few cooling passages.
3. An internal combustion engine having a water and steam cooling circuit of inadequate radiating capacity, serially including a force feed pump supplying water to the jacket of the engine, an outlet discharging hot water and steam from the jacket into the lower chamber of an air cooled radiator of the upright type having a multiplicity of small diameter cooling passages of great radiating capacity connecting a lower chamber of small radiating capacity with an upper chamber which has a high level overflow outlet, and in combination with said parts, means for maintaining a circulating body of water submerging and upflowing through some of said cooling passages and downward through others, said means including an injector discharge device in the lower chamber arranged to discharge hot fluid from the engine lengthwise along a region of said body of water that is below and in proximity to the lower ends of a large number of said cooling passages, the suction intake of said injector being in proximity to the lower ends of relatively few cooling passages, and partition means.
4. An internal combustion engine having a water and steam cooling circuit of inadequate radiating capacity, serially including a force feed pump supplying water to the jacket of the engine, an outlet discharging hot water and steam from the jacket into the lower chamber of an air cooled radiator of the upright type having a multiplicity of small diameter cooling passages of great radiating capacity connecting a lower chamber of small radiating capacity with an upper chamber which has a high level overflow outlet, and in combination with said parts, means for maintaining a circulating body of water submerging and upflowing through some of said cooling passages and downward through others, said means including an injector discharge device in the lower chamber arranged to discharge hot fluid from the engine lengthwise along a region of said body of water that is below and in proximity to the lower ends of a large number of said cooling passages.
5. An internal combustion engine having a water and steam cooling circuit of inadequate radiating capacity, serially including a force feed pump supplying water to the jacket of the engine, an outlet discharging hot water and steam from the jacket into the lower chamber of an air cooled radiator of the upright type having a multiplicity of small diameter cooling passages of great radiating capacity connecting a lower chamber of small radiating capacity with an upper chamber which has a high level overflow outlet, and in combination with said parts, means for maintaining a circulating body of water submerging and upflowing through some of said cooling passages and downward through others, said means including an injector discharge device in the lower chamber arranged to discharge hot fluid from the engine lengthwise along a region of said body of water that is below and in proximity to the lower ends of a large number of said cooling passages, the suction intake of said injector being in proximity to the lower ends of relatively few cooling passages, and partition means.

separating the intake region from the discharge region.

6. An internal combustion engine having a water and steam cooling circuit of inadequate radiating capacity, serially including a force feed pump supplying water to the jacket of the engine, an outlet discharging hot water and steam from the jacket into the lower chamber of an air cooled radiator of the upright type having a multiplicity of small diameter cooling passages of great radiating capacity connecting a lower chamber of small radiating capacity with an upper chamber which has a high level overflow outlet, and in combination with said parts, means for maintaining a circulating body of water submerging said cooling passages, upflowing through some of them and downward through others, said means including a discharge device having a multiplicity of outlets arranged to cause high velocity discharge of hot water and steam from the engine lengthwise along a region of said body of water that is below and in proximity to the lower ends of a large number of said cooling passages, the intake of the pump being arranged to maintain an active cycle of boiling and condensing varying with the operations of the automotive parts, by withdrawing highly heated water from the region of said hot water discharge in said lower chamber.

7. An internal combustion engine having a water and steam cooling circuit of inadequate radiating capacity, serially including a force feed pump supplying water to the jacket of the engine, an outlet discharging hot water and steam from the jacket into the lower chamber of an air cooled radiator of the upright type having a multiplicity of small diameter cooling passages of great radiating capacity connecting a lower chamber of small radiating capacity with an upper chamber which has a high level overflow outlet, and in combination with said parts, means for maintaining a circulating body of water submerging and upflowing through some of said cooling passages and downward through others, said means including a discharge device for hot water and steam from the engine, discharging from one side of the lower chamber lengthwise along a region of said body of water that is below and in proximity to the lower ends of the central passages as well as those beyond the same.

8. An internal combustion engine having a water and steam cooling circuit of inadequate radiating capacity, serially including a force feed pump supplying water to the jacket of the engine, an outlet discharging hot water and steam from the jacket into the lower chamber of an air cooled radiator of the upright type having a multiplicity of small diameter cooling passages of great

radiating capacity connecting a lower chamber of small radiating capacity with an upper chamber which has a high level overflow outlet, and in combination with said parts, means for maintaining a circulating body of water submerging and upflowing through some of said cooling passages and downward through others, said means including a discharge device for hot water and steam from the engine, discharging from one side of the lower chamber lengthwise along a region of said body of water that is below and in proximity to the lower ends of the central passages as well as those beyond the same, said discharge device being in the form of an injector nozzle with a tube surrounding the jet therefrom.

9. An internal combustion engine having a water and steam cooling circuit of inadequate radiating capacity, serially including a force feed pump supplying water to the jacket of the engine, an outlet discharging hot water and steam from the jacket into the lower chamber of an air cooled radiator of the upright type having a multiplicity of small diameter cooling passages of great radiating capacity connecting a lower chamber of small radiating capacity with an upper chamber which has a high level overflow outlet, and in combination with said parts, means for maintaining a circulating body of water submerging and upflowing through some of said cooling passages and downward through others, said means including a discharge device having a multiplicity of outlets arranged to cause high velocity discharge of hot water and steam from the engine, discharging from one side of the lower chamber lengthwise along a region of said body of water that is below and in proximity to the lower ends of the central passages as well as those beyond the same, said discharge device being in the form of an injector nozzle with a tube surrounding the jet therefrom.

10. An internal combustion engine having a water and steam cooling circuit of inadequate radiating capacity, serially including a force feed pump supplying water to the jacket of the engine, an outlet discharging hot water and steam from the jacket into the lower chamber of an air cooled radiator of the upright type having a multiplicity of small diameter cooling passages of great radiating capacity connecting a lower chamber of small radiating capacity with an upper chamber which has a high level overflow outlet, and in combination with said parts, means for maintaining a circulating body of water submerging and upflowing through some of said cooling passages and downward through others, said means including a discharge device for hot water and steam from the engine, discharging from one side of the lower chamber lengthwise along a region of said body of water that is

below and in proximity to the lower ends of the central passages as well as those beyond the same, said discharge device being in the form of an injector nozzle with a tube surrounding the jet therefrom, the tube and the jet being a single casting and having support means whereby the tube and also the inlet end of the nozzle are anchored in and to the lower chamber.

Signed at Plainfield, in the county of ¹⁰ Union, and State of New Jersey, this ninth day of August, A. D. 1926.

SAMUEL W. RUSHMORE.
